SLUG-REJECTING COIN SLIDE

Louis M. Hall, Fort Thomas, Ky., assignor to The
Monarch Tool & Manufacturing Company,
Cincinnati, Ohio, a corporation of Ohio

Application February 3, 1934, Serial No. 709,621

2 Claims. (Cl. 194—100)

This invention relates to a manually operated coin-controlled mechanism for use with various mechanical devices which release one or more objects to the operator upon deposit of a coin and actuation of the device of this invention.

An object of the invention is to provide a device of the class described which may not be actuated upon insertion therein of a coin of a denomination other than that which the device is made to receive, nor by slugs of cardboard, lead, fiber or other non-magnetic comparatively soft material, nor by slugs, perforate or imperforate, of magnetic material such as iron or steel, even though all of these may be of proper diameter and thickness.

Another object of the invention is to provide a device of the class described in which an operator who either deliberately or accidentally makes use of a coin of the wrong denomination, must withdraw the coin from the device rather than lose the coin, as in similar mechanisms heretofore constructed.

Other objects of the invention are: to provide a device of the character stated which may be manufactured inexpensively and with a minimum of labor; to provide such a device with means whereby it may easily and inexpensively be converted to receive and operate by the use of coins of different denominations; to provide an effective, simple, and durable ratchet mechanism for precluding recovery of the inserted coin after the coin has been advanced a predetermined distance; and to provide such device with a slug cutter or mutilator which functions to preclude entry of the slug to the extent necessary for releasing the objects to be dispensed.

The foregoing and other objects are attained by the means described herein and disclosed in the accompanying drawings, in which:

Fig. 1 is a plan view of the device of the invention.

Fig. 2 is a side view of the Fig. 1 device.

Fig. 3 is a fragmental plan view of the coin slide or actuating member.

Fig. 4 is a plan view of a double-acting ratchet member or pawl which cooperates with certain notches formed along one side edge of the coin slide.

Fig. 5 is a plan view, part being broken away, showing the body of the device with the top plate, the coin slide, and the slug detecting magnet removed therefrom.

Fig. 6 is a side view of the top plate and its associated slug rejecting elements.

Fig. 7 is a view similar to Fig. 5, showing the coin slide in a partly advanced position.

Fig. 8 is a cross-sectional view taken on line 8—8 of Fig. 2.

Fig. 9 is a cross-sectional view taken on line 9—9 of Fig. 5.

Fig. 10 is a cross-sectional view taken on line 10—10 of Fig. 3.

The device of this invention is designed to preclude improper operation of the device and to return to the operator any coin or slug other than the kind which the device is intended to receive, thereby precluding jamming and possible injury to the device and precluding also the likelihood of putting the device out of service. For convenience of description and explanation, the device will be set forth as a nickel receiving apparatus, it being understood however, that a simple change in proportions of the coin-receiving and operating parts is all that is necessary to provide for operation of the device by pennies, dimes, quarters or other coins of uniform proportions. It is to be observed that one object of the invention is specifically to provide a construction whereby the changes required for rendering the device properly receptive of different coin denominations, may be accomplished with a minimum of labor and expense. The provision of a novel and effective slug cutter which dents or shaves the slug edge is also an important feature of the device about to be described.

In the drawings, 12 indicates a guide member or plate which has suitable longitudinal bearing or guide channels 13 and 14 for slidably receiving the side edges 15 and 16 of a coin slide or coin advancing member 17. The member 17 preferably is in the form of a substantially flat longitudinal strip having the forward handle end 18 and a rear end 19. The coin side is adapted to be advanced from the inoperative extended position and a rear end 19. The coin slide is adapted to be described later), at which the handle end is disposed a short distance from the mounting plate 20, and at which position the coin is delivered by the slide to any suitable receiver or till at the right-hand side of the mounting plate. The guide member 12 will be seen to extend both forwardly and rearwardly of the mounting plate 20.

In the normal or inoperative position of the coin slide, (Fig. 1), an aperture 21 therein, for the reception of nickels, registers substantially with an exposed cut-away portion 22 of the part 12 so that such coin may be placed within the aperture 21 and advanced by the slide while 55

resting upon the bottom wall 23 of the guide plate or member 12. A finger hole 24 is provided in the bottom wall 23 to enable the operator to easily remove a coin inadvertently placed in the opening 21, before advancement of the slide to an appreciable extent.

It is of importance to note that the aperture 21 of the slide is located off-center, (Fig. 3), and that it has a mouth or cut-out at the edge 16 of the slide bounded by a pair of opposed abutments 25 and 26. Abutment 25 is a dog stop, and is formed in part by the edge 16 of the slide. The abutment 26 is a dog guide, and is located inwardly of the slide edge 16 but associated therewith, in a sense, by reason of the connecting incline or track portion 27. The distance between the abutments 25 and 26 is less than the diameter of aperture 21. The abutments are adapted to cooperate with the stop end 28 and the chisel or cutter part 29 of a slug intercepting dog 30, in a manner to be described later.

Behind the mounting plate 20, the bottom wall 23 of guide plate 12 is cut away to provide a coin release aperture 31, (Figs. 5 and 9), but this aperture is closed from its forward end 32 to a point 33, by means of a coin supporting wall or floor plate 34. It is immaterial whether the member 34 is integral with guide plate 12 or attached thereto by means of screws or other fastening means such as 35, but it is important that the member 34 shall be properly shaped to provide a well or depressed coin supporting surface 36 which lies in a plane below and spaced from the slide or its guides 13-14 a distance not less than the thickness of the coin intended to properly operate the mechanism. The forward end 37 of the plate or wall member 34 lies in the plane of the bottom wall 23, so that the coin will be supported thereon until the well or pocket is reached as the slide is advanced or depressed. Upon complete advancement of the coin slide, the proper kind of coin will be pushed along the surface 37, down onto and along the depressed surface 36, and over the rear edge 38 of member 34, whence the coin will fall through the coin-releasing aperture 31 and into a suitable receiver, not shown. The well or depressed pocket structure just described is set forth fully in applicant's United States Patent of May 16, 1933, numbered 1,908,752.

The upper wall 39 of guide plate 12 is cut away in the shape of an ordinary horse-shoe magnet as at 40, to receive and hold stationary a magnet 41 in close proximity with the upper surface of the coin slide. It is to be noted that the poles of the magnet overlie the elevated portion 37 of the pocket-forming or well-forming member 34. The weight of the magnet advantageously may be supported directly by the coin slide, if desired, as this construction avoids the necessity of closely fitting the magnet in its holding socket or aperture 40. Due to the off-center disposition of the coin slide aperture 21, the magnet poles are required to be disposed to one side of the guide plate, nearest the guide-way 14, so that both poles may act effectively to attract a magnetic coin or slug that may be introduced into the device. The off-center disposition of these parts will be more fully treated hereinafter, as it is necessary to first describe and explain the functions of other parts.

Attention is now directed to Figs. 1, 2 and 6 which show a trigger mechanism that forms part of the invention. The trigger mechanism is supported upon a so-called top plate 42 which may

be screwed onto the top surface 39 of the guide plate 12 so as to cover and hold the magnet 41 in place. The top plate 42 has fixedly mounted thereon a vertically disposed bracket 43 which carries a pivot 44 for pivotally supporting a vertically movable trigger member 45. The trigger member has a downwardly turned nose or projection 46, which extends through an opening or slot 47 of the top plate directly above a line drawn through the center of aperture 21 in parallelism with the side edges of the coin slide. A spring 48 mounted atop the bracket 43, contacts the nose end of the trigger member for the purpose of yieldingly projecting the nose through the aperture 21 when the slide is advanced without insertion of a coin into the coin slide aperture 21. The nose 46 thereby contacts the forward portion of the aperture wall, to preclude further advancement of the coin slide, when the slide is partly advanced without insertion of a coin. The nose 46 may enter also the aperture 32, through the opening 57 of plate 34.

Intermediate the nose end and the pivot end of the trigger member is a depending lug or projection 49 which is adapted to ride upon the coin slide as said slide is moved longitudinally. Normally, the lug 49 rests atop the slide, upon an elevated track portion 50 immediately behind a straight longitudinal depressed track portion or groove 51. The groove has a bottom wall 52, formed by a longitudinal off-center strip, rib or guide piece 53 which extends below the coin slide as indicated in Figs. 8 and 10. The guide piece 53 extends from a point near the rear end of the slide, forwardly to the aperture 21 where it is broken, and it continues forwardly a short distance from said aperture as shown in Fig. 10. The inclines 54 and 55 provide for easy movement of the lug 49 and nose 46, respectively, into and out of the depressed track portion or groove 51 of the coin slide. It is to be understood that both of the elements 49 and 46 are adapted to ride in the groove, at certain times. The guide strip 53 has a coin-advancing end or abutment 56, near the forward edge of aperture 21, which end is adapted to move within a slot or way 57 of the depressed plate portion 36 of the well, so as to closely overlie the depressed plate portion and thereby dislodge from the well any coin that may fall into the depressed portion when advanced thereto by the coin slide. The opposed end or abutment 56 is provided to abut the coin and preclude retraction of the slide in the event that the abutment 56 fails, due to insufficient slide advancement, to eject the coin from the well.

The longitudinal strip forming the coin dislodging abutment 56 is slidable in a relatively wide groove 58 formed in the bottom wall 23 of the guide plate 12, this groove being extended both forwardly and rearwardly of the finger hole 24. The groove is formed off-center of the guide plate, like the opening 24, so as to receive the off-center coin pushing element 56 of the coin slide. The purpose of off-centering the elements 58, 24, 56, 52, 21 and magnet 41, and of providing the wide slot 58, is to enable the manufacturer to transform the device into a dime, quarter, or penny receiving device by simply enlarging or decreasing the diameter of the coin slide aperture 21 and furnishing a differently slotted plate 34. No part of the entire guide plate 12 need be changed, other than the removable well member 34, to effect the transformation necessary to adapt the device for reception of coins of different denominations.

nations. As will be understood, the longitudinal coin pusher element 53 of Fig. 8 will assume different positions within the wide guide slot 58 according as the coin-receiving aperture 21 of the coin slide is drilled larger or made smaller to receive coins of different diameters. When the coin slide is thus altered to receive coins of different diameters, proper care is taken to drill the holes such as 21 in order that there will be provided 5 on the coin slide edge 16 the various abutments 25, 26 and 27 (Fig. 3), to cooperate with the cutting or chiseling dog 30, in a manner about to be described.

As is clearly seen from the disclosure of Fig. 1, 15 the cutter portion 29 normally rests with its flat portion 59 against the edge 16 of the coin slide, whereby to hold the stop end 28 thereof spaced from the coin slide edge 16. As the slide is advanced, however, the dog element 59 slides inwardly over the incline 27, due to the yielding action of a spring 60, to place the abutment 28 of the dog in position to engage the abutment 25 of the coin slide and to thereby effectively arrest further advancing movement of the coin slide in 20 the manner illustrated in Fig. 7. The foregoing described action results when no coin is placed in the coin slide aperture 21. It may be remarked at this time that the nose 46 of the trigger member 45 will also move down into position within 25 the aperture 21 to enter the coin slide aperture 21. The trigger nose may strike the abutment 56 before the dog end 28 abuts the projection 25, if desired, to relieve the dog of the function of stopping the slide, however, the real function of 30 the trigger nose is to enter the central openings of washers or perforated slugs or coins. It is in fact immaterial whether the advancing movement of the coin slide is arrested by the trigger nose 46 or by the dog end 28, in the event that a coin 35 is absent from the coin slide aperture 21. The dog 30 is pivoted upon the guide plate 12 as at 61, to lie in the plane of the coin slide member 17 adjacent to its side edge 16, as will be apparent from Fig. 2.

The element indicated by the character 62 (Figs. 2 and 6), is a fixed stop carried by the top plate 42 and arranged to depend always into the groove 51 of the coin slide at a location slightly forwardly of the trigger actuator 49, and above 50 the well or depressed portion 36 of plate 34. The stop element 62 and its function is set forth in combination with the well or depressed pocket structure in applicant's United States patent of May 16, 1933, No. 1,908,752. As is apparent by 55 referring to Fig. 2, any coin or slug remaining in the plane of the coin slide while disposed over the well, will have its advancing edge to contact the stop 62, whereby to limit the advancement of the slide. The foregoing will result when a slug of 60 magnetic material is precluded, by magnet 41, from dropping into the well at 36. Such a slug, being held within the coin slide aperture 21 by the attraction of magnet 41, obviously will be returned to the operator when the coin slide is retracted by him. The complete operation of the 65 mechanism will not be set forth in detail, however, until completion of the description.

Means are provided for precluding retraction of the coin slide after it has been advanced a pre-determined distance, or the distance necessary to 70 operate a dispensing device such as is customarily associated with coin control devices. Said means comprises a jamb plate or member 63 (Figs. 4 and 9), having an upper lobe or ear pivoted 75 loosely as at 64 upon an upwardly directed exten-

sion 65 of the guide plate, said guide plate being apertured at 66, above the coin slide edge 15, to permit the jamb plate to depend vertically into one or the other of a pair of enlarged notches 67 or 68 in the coin slide. The coin slide is provided, 5 intermediate the notches 67 and 68 and along the edge 15, with a series of short notches 69 into which the corners 70 or 71 of the jamb plate may engage according as the slide is advanced or retracted in an improper manner to secure repeated 10 delivery of articles from the dispenser with the use of a single coin. As will be understood by referring to Figs. 3, 5 and 9, advancement of the slide 15 will cause the edge 72 of notch 68 to strike the sliding face 73 of the jamb plate, whereby 15 to slightly rotate the plate and cause its corner 70 to slide atop the edge portion of the coin slide. As the corner 70 passes over the series of notches 69 and falls into each of them, any attempt to retract the coin slide results in a binding or jambing 20 action between a notch 69 and the lower jambing surface 74 of the jamb plate. However, when the slide is advanced sufficiently to dispose the forward notch 67 in registry with the jamb plate, the jamb plate assumes a vertical position, 25 at which the coin slide is free to be retracted. Upon retracting the coin slide, the other sliding surface 75 of the jamb plate bumps over the notches 69, leaving the points 71 always in readiness to jamb the slide upon an attempt to improperly 30 reverse the movement of the coin slide while the notches 69 are disposed in the vicinity of the jamb plate. The characters 76 indicate seats on the jamb plate for reception of a pair of spring arms 77 (Fig. 1) which serve to yieldingly hold the jamb plate always in the vertical or normal position shown in Fig. 9. The spring just mentioned may be secured to the top plate 42 as indicated at 78.

The operation of the device is as follows: 40

Assuming that there is no coin within the coin slide aperture 21, and that the slide 15 be advanced by an operator of the device, by referring to Figs. 2 and 3 it will be observed that the slide will advance until the stud 49 descends the incline 45 54 and thereby lowers the forward end or nose 46 downwardly through the aperture 21, thereby causing the abutment 56 to strike the forward surface of nose 46 and consequently terminate inward advancement of the coin slide member. 50 The slight movement afforded the slide under the conditions just mentioned is insufficient to actuate a dispensing device with which the coin control device is associated. A slide partially advanced as above explained, may be retracted to 55 the original or inoperative position, during which retractile movement the incline 54 will act upon the lug 49 of the trigger member to elevate the nose 46 to the non-intercepting position of Fig. 2.

Assuming now that a perforated coin or washer 60 be inserted in the coin slide aperture 21, advancement of the coin slide member will result in lowering the trigger nose 46 into the perforation of such apertured coin or washer, thereby likewise precluding appreciable advancing movement 65 of the slide. The rearmost edge of nose 46 being inclined upwardly, there will be no tendency of the trigger nose to hold the perforated coin or slug, wherefore the slide may be withdrawn to the initial position and the improper coin or slug 70 removed.

When the proper coin is deposited in the coin slide aperture 21, the slide will advance freely, the nose 46 riding over the top surface of the coin and permitting the coin to pass onto the 75

elevated portion 37 of the plate 34, whereupon further movement of the slide and coin results in dropping of the coin through the aperture 21 and onto the depressed or lowered supporting wall 36 of plate 34. When the coin is thus deposited upon the surface 36, the coin is no longer under the influence of the advancing action of aperture 21, but the coin pushing projection 56 on the bottom of the coin slide then completes the rearward movement of the coin by moving it rearwardly along surface 38 until it drops over the edge 38 and through the coin releasing aperture 31. During the early part of the coin-advancing movement just explained, the chisel or cutting-part 29 of dog 30 had, under the influence of spring 60, moved down the incline 21 of the coin slide member 15 so as to place the abutting end 29 of the dog in position to strike the abutment 25 of the coin slide, but the periphery of the coin as it rested in the opening 21, struck the extension 29 of the dog and moved its end 28 from alignment with the abutment 25, in sufficient time to allow the abutment 25 to pass the dog 30.

The above described action of dog 30 is different, however, when a slug of cardboard, lead, or other comparatively soft material of the proper size is inserted in the coin-receiving aperture 21 of the slide member. Assuming that a soft lead slug be placed in the aperture 21, and that the slug be of the same diameter as a nickel, the chisel or cutter-point or edge 29 will dig into or indent the soft metal edge of the slug and thereby permit the stop end 28 of dog 30 to move into engagement with the abutment 25 of the coin slide member. Thus, there is precluded all further advancement of the slide member. The same action results when a slug of cardboard or other soft material of proper coin diameter is placed within the coin-receiving aperture 21 in an attempt to operate the mechanism for delivery of an article to be dispensed.

If a coin or slug of smaller diameter than the intended coin be inserted into the receiving aperture 21, the extending lug 29 of the dog will not be acted upon by such smaller coin or slug to remove the abutting end 28 of the dog from the path of movement of the slide abutment 25, wherefore, the advancing movement of the slide 50 will be terminated when the elements 28 and 25 abut, or in other words, prior to an appreciable advancement of the slide member.

It is to be observed that in each of the above circumstances, where the slug or coin was either 55 too small, too soft, or perforated through its central portion, it was imperative that such slug or coin of improper proportion or shape be retracted by the slide member rather than retained within the mechanism. The necessary withdrawal of the improper coin or slug obviously 60 precluded all possibility of jamming the mechanism and putting the device out of service.

It will now be assumed that a slug of the proper diameter, but of a magnetic material such 65 as iron or steel, is inserted into the coin-receiving aperture 21 in the attempt to actuate the device. Under these conditions, the magnetic slug of proper diameter will be advanced when the slide is advanced, and the slug, being of 70 proper size and of hard material, will actuate the dog 30 just as a nickel would move the dog to prevent engagement of the abutments 28 and 25. However, as the magnetic slug moved over the elevated portion 37 of plate 34, and toward the 75 well or depressed portion 36 of the plate, the

magnet would attract the magnetic slug and preclude its falling on the depressed surface 36. The magnetic slug, being maintained in an elevated position by the action of the magnet, would necessarily have its advancing edge come into contact with the depending stop 62 (Figs. 2 and 6), thereby precluding complete advancement of the slide member. Inasmuch as the magnet thereby retains the magnetic slug within the coin aperture 21 of the slide, it is imperative that the slug be returned to the operator upon withdrawal of the slide member. It will be understood, of course, that a coin of non-magnetic material, with which the device is adapted to operate, would never strike the stop 62 because such proper coin would have to drop into the well portion 36 before reaching the stop 62. As will be understood by those skilled in the art to which this invention relates, any suitable type of actuating member 80 would be associated with the coin slide and with a dispensing device, so as to dispense articles only upon advancement of the coin slide to the fully extended position. As all types of slugs and improper coins have the effect of precluding complete advancement of the coin slide member, it therefore follows that no articles would be dispensed with the use of slugs or coins of improper diameter or of comparatively soft material.

The action of the jamb plate 63 for precluding 30 improper manipulation of the coin slide member has been fully set forth in a preceding paragraph.

Attention is directed particularly to the offset or off-center disposition of the various parts of the coin slide and associated mechanism, whereby the parts 25, 26, and 27 which are necessary complements for the noses 28 and 29 of dog 30, may easily and inexpensively be formed regardless of the size of coin aperture 21 to be provided, without changing the location of any of the guide plate elements excepting the easily replaceable plate 34. Thus, the same guide plate structure is used in making coin control devices operating by the use of nickels, dimes, quarters, pennies or any other denomination of coin. Heretofore 45 it was necessary to use many different dies and different machine settings in manufacturing coin control devices for nickel, dime, penny and quarter machines, but most of this has been eliminated by utilizing the off-center construction 50 and the edgewise disposed dog 30. It is noteworthy also that any and all slugs, or coins of the wrong diameter, are returned to the operator, thereby precluding jamming of the mechanism and putting the device out of service. The 55 provision of a slug edge cutting or denting dog also is considered a novel and very desirable feature of the device.

It is to be understood that various modifications and changes in the structural details of the 60 device may be made, within the scope of the appended claims, without departing from the spirit of the invention.

What is claimed is:

1. In a device of the class described, the combination of a guide plate providing a slide guide, a coin slide receivable in said guide for sliding advancement and retraction longitudinally, said slide having one longitudinal side edge cut away to provide an open-sided coin receiving aperture 70 through which a part of the periphery of a coin or soft slug resting in said aperture is exposed in the plane of the slide, means operating upon advancement of the slide to indent a soft slug and arrest the advancing movement of the 75

slide, a narrow off-center depending strip on the slide the major axis of which strip passes approximately through a diameter of the coin receiving aperture, a relatively wide cooperative groove in the guide plate for reception of said off-center depending strip, and a horse-shoe magnet supported over the coin slide with its poles disposed in off-center relationship relative to the coin slide so that the poles will overlie the off-center coin receiving aperture when the slide is advanced, whereby the location of the magnet, the guide plate channel, and the slug indenting and slide arresting means, may remain in the aforesaid cooperative positions and still perform their respective functions although the open-sided coin receiving aperture be enlarged or reduced in diameter for reception of coins of different denominations.

2. In a device of the class described, the combination of a guide plate providing a slide guiding means and having in its upper face a longitudinal groove, a coin slide received in said guiding means for sliding advancement and retraction longitudinally, said slide having one longitudinal side edge cut away to provide an open-sided coin receiving aperture through which a

part of the periphery of a coin or soft slug resting in said aperture is exposed in the plane of the slide, means operating upon advancement of the slide to indent a soft slug placed within the aperture, means for precluding full advancement of said slide upon operation of the indenting means, an off-center depending rib on the slide the major axis of which rib passes approximately along a diameter of the coin receiving aperture, said rib being considerably narrower than the longitudinal groove in the upper face of the guide plate so as to be received in said groove with abnormal lateral clearance, a magnet supported over the coin slide with its poles substantially straddling the axis of the aforesaid rib, and a well-carrying plate fixed beneath the slide, said plate having a longitudinal way therein of approximately the width of the guide plate groove and substantially in alignment with said groove, to permit movement of the depending rib therein, the aforesaid arrangement being for the purpose of rendering all the parts operatively related even though the coin slide aperture be changed in diameter to receive coins of different sizes.
